METHOD OF MAKING FLEXIBLE TUBING

Hartwell W. Webb, Flint, Mich., assignor to General Motors Corporation, Detroit, Mich., a corporation of Delaware

Application September 11, 1936, Serial No. 100,296

2 Claims. (Cl. 113—35)

This invention relates to the method of making flexible tubing or casing used to house the flexible shaft used to drive the speedometer in automotive vehicles. The tubing is, however, 5 capable of use in many other relations.

In the prior art it is known to form a casing or flexible tubing of two spirally intertwined members one of which is relatively flat and broad and the other relatively narrow and of triangular 10 shape. It has been found that where a flexible tubing is made with the small triangular member spirally wound between the convolutions of the relatively broad member the tubing will have a tendency to "crack" or "break" when given too 15 small a bending radius. This cracking or breaking is objectionable in that the tube could not be easily restored to its original shape. In investigating the cause of this cracking or breaking 20 it was found that if the relatively narrow triangular element of the casing was made with dished arcuate sides and the shape of the sides of the arc made to conform with the rounded shape of the relatively broad member, a better 25 casing could be made by bending or flattening the edge of the triangular member where it contacts with the broader element of the casing. This flattening or bending is caused by the rolls 30 in winding the wire to circular form when the casing is made. The triangular member before it is formed into the casing has its outer side curved or inwardly dished, but in the finished form of the cable the outer face is substantially 35 flat or straight for the reason that the edges of the element (adjacent the broad element of the tubing) have been curled down or bent toward the casing. This curling down or bending of the 40 arcuate edge gives a closer contact between the adjacent elements of the casing and also prevents the cracking or breaking of the cable when given a relatively short radius of curvature.

On the drawing

Figure 1 is a view of the wire passing through the pairs of forming rolls.

Figure 2 is an enlarged sectional detailed view through the completed casing.

Figure 3 shows in section the finished wire rolled into triangular form for a large diameter 50 casing.

Figure 4 shows in section the manner of rolling a triangular wire from the first pair of rolls into triangular form with arcuate sides for a large diameter casing, the section being taken 55 through the rolls at the left of Figure 1.

Figure 5 is a view of the rolls for forming the wire to the shape shown in Figures 3 and 4.

Figure 6 is a view of the finished casing.

On the drawing the numeral 2 indicates a 5 flexible tubing or casing. The tubing is composed of two coiled or intertwined elements 4 and 6. The element 4 is relatively flat and has an inside flat surface 8 and an outer arcuate or curved surface 10. The element 6 is in general 10 form triangular, but has its side faces rounded 15 inwardly or in arcuate form as shown at 12. Its top or outer face 14 is also arcuate and rounded inwardly as best shown in Figure 3. The curvature of the side face 12 conforms to the 20 curvature of the side of the elements 10 as 25 indicated at 16.

Referring to Figures 1, 4, and 5, the pairs of 30 rollers 15 and 17, 18 and 20 for forming the 35 triangular element 6 are shown. The upper roller 15 is cylindrical while the lower roller 17 has a V-groove 19 to give a preliminary V-shape to the round wire 21. The second upper roller 18 has the annular ribs 22 and 24, while the lower roller 20 has the mating or registering 40 annular grooves 26 and 28. The groove 26 conforms to the rib 22 while the groove 28 conforms to the rib 24. A section through the rib 22 in groove 26 is shown in Figure 4. A circular 45 wire is used and is first passed between the rolls 15 and 17 to cause the roller 15 and groove 30 19 to give it a triangular shape at 6' in Figure 1. This triangular wire is then passed through the 40 rolls 18 and 20 between the rib 22 and groove 26 to give it the finished shape as shown at 6 in Figures 1 and 3. This shape is used for larger 45 diameter casings.

The form of the rib 24 and groove 28 are 50 dimensionally different but give a finished product of a shape similar to that of Figure 3. The change in shape is to adapt the wire to small 55 diameter casings.

By referring to Figures 3 and 4 it will be noted 60 that the upper inwardly dished curved surface 14 has the outer upwardly projecting edges 30 and 32. When the element 6 is placed in the 65 machine to form the flexible casing 2 to the form shown in Figure 6 the rollers of the machine will flatten or curl down the upwardly projecting edges 30 and 32 and spread them laterally 70 over the surface 10 and cause the element 6 to be substantially flat at its outer surface as shown at 30' and 32' in Figure 2. This flattening or 75 curling down of the edges 30 and 32 which takes place during the forming operation will press the 80 contacting sides at 16 closer together and give 85

to the element 6 and the flexible casing in general a permanent set so that it will not uncurl at the ends and so that there is a much less tendency to break or crack when the casing is given 5 a sharp arcuate curve.

I claim:

1. The method of making flexible tubing consisting of spirally intertwining a relatively flat element having an arcuate surface and a substantially triangular element having arcuate dished sides and an arcuate dished top, the intertwining of said elements into tubular form causing the two arcuate sides of the triangular member to contact with the adjacent arcuate 10 sides of the relatively flat member and flattening or rolling down of the edges of the outer or top arcuate side of the triangular member to cause 15

a firmer contact between the two spirals and to give a permanent set to the elements of the tubing and to prevent unraveling.

2. The method of making flexible tubing consisting of spirally intertwining a relatively flat element having sloping edge surfaces and a substantially triangular element having sloping sides and a dished top, the intertwining of said elements into tubular form causing the two sloping sides of the triangular member to contact with 10 the adjacent sloping sides of the relatively flat member and flattening or rolling down of the edges of the dished top of the triangular member to cause a firmer contact between the two spirals and to give a permanent set to the elements of the tubing to prevent unraveling. 15
